UNITED STATES PATENT OFFICE

125,021

DESIGN FOR A JACKET OR THE LIKE

Hyman Goodman and Sidney Goldman,
Chicago, Ill.

Application May 23, 1940, Serial No. 92,535

Term of patent 3½ years

To all whom it may concern:

Be it known that we, Hyman Goodman and Sidney Goldman, citizens of the United States, residing at Chicago, in the county of Cook and State of Illinois, have invented a new, original, and ornamental Design for a Jacket or the like, of which the following is a specification, reference being had to the accompanying drawing, forming part thereof.

Fig. 1 is a front view of a jacket showing our new design.

Fig. 2 is a rear view of same.

We claim:

The ornamental design for a jacket or the like, as shown.

HYMAN GOODMAN.
SIDNEY GOLDMAN.
